UNITED STATES PATENT OFFICE

119,867

DESIGN FOR A PARING AND CORING TOOL

James A. Murdock, Chicago, Ill.

Application February 12, 1940, Serial No. 90,215

Term of patent 14 years

To all whom it may concern:

Be it known that I, James A. Murdock, a citizen of the United States, residing at Chicago, in the county of Cook and State of Illinois, have invented a new, original, and ornamental Design for a Paring and Coring Tool, of which the following is a specification, reference being had to the accompanying drawing, forming part thereof.

Figure 1 is a perspective view of the paring and coring tool embodying my new design.

Figure 2 is a plan view thereof.

Figure 3 is a side elevation thereof.

I claim:

The ornamental design for a paring and coring tool, as shown.

JAMES A. MURDOCK.
